ION SOURCE

Clarence W. Blue, Knoxville, and John S. Luce, Oak Ridge, Tenn., assignors to the United States of America as represented by the United States Atomic Energy Commission

Filed Sept. 3, 1959, Ser. No. 838,009

8 Claims. (Cl. 313—63)

This invention relates to ion sources, and more particularly to a novel method of and means for generating ions external to or within a magnetic field and withdrawing ions at an acute angle to that field.

Ion sources are used to furnish ions for particle accelerators. They are used also in experimental thermonuclear research, and in thermonuclear fusion devices. The latter devices produce energetic neutrons which are useful in bombarding materials, for example, in studies of radiation interaction with matter.

One of the problems encountered in the development of successful thermonuclear devices involves generating, injecting, and retaining ions in a magnetic mirror field. When ions are accelerated from an ion source perpendicularly into a uniform magnetic field, they are bent into a circular orbit. The ions then return and strike the source on their first turn in the magnetic field, and thus are lost to the system. If the ions are given sufficient angular displacement in the direction along the field, they will travel away from the source in a spiral orbit. If injected between magnetic mirrors, they will return after their first reflection and strike the source, regardless of their original angle of entry into the magnetic field.

It is desirable to inject ions into the magnetic field of a controlled thermonuclear machine in such a direction that the path of the ions diverges substantially from the direction of the magnetic field and yet ions will not return to strike the ion source. It is also desirable to inject ions having orbits oriented at a large angle to the axis of the machine in order to minimize the loss of ions through the magnetic mirrors. For example, it has been shown that the minimum (critical) angle, θ_c , between magnetic field and ion entrance path at which ions will be retained in the mirror region is obtained from the expression:

$$\sin^2 \theta_c = \frac{B_0}{B_1}$$

where:

B_0 =magnitude of the uniform flux between the mirrors;
 B_1 =maximum value of the mirror flux;

where $B_0/B_1=1/4$, for example, $\theta_c=30^\circ$.

With a knowledge of the problem of retaining ions in a magnetic field because of their returning to strike the source, it is a primary object of this invention to provide a method for injecting ions from an ion source into a magnetic field such that the ions will be retained and will not return to strike the source.

It is another object of this invention to provide an ion source wherein ions are injected in such a direction that their direction of motion is highly divergent from the direction of the magnetic field.

These and other objects and advantages of this invention will become apparent from a consideration of the following detailed description and the accompanying drawings wherein:

2

Figure 1 is a cross-sectional view of the ion source utilizing a cylindrical arc discharge.

Figure 2 is an enlarged cross-sectional view of the cylindrical arc discharge structure of Figure 1, and

Figure 3 is an enlarged cross-sectional view of a small solid arc discharge which may be substituted for cylindrical arc discharge of Figure 1.

The above objects have been accomplished in the present invention by establishing an arc discharge parallel to the direction of and inside a magnetic field, surrounding substantially all the discharge with an accelerating electrode, except for an ion exit aperture, and establishing an electric field between that electrode and the arc, the electric field being oriented at an acute angle to the magnetic field. Ions are drawn through exit apertures in the accelerating electrode in a direction substantially divergent to the direction of the magnetic field and so will travel in a spiral orbit along the magnetic field. Thus, ion motion is directed away from the source so that the ions will not strike the source at any point in their orbit within the field. When the ions from the above source are injected into a magnetic mirror field, the source is positioned in the magnetic mirror field near one end and the ions are then injected into a pulsed, time-rising magnetic field. This time-rising magnetic field is required to prevent the ions, after being reflected by the mirror field in the other end of the device, from returning and striking the source. The ion injection is continued until the magnetic field has increased with time to a predetermined value, after which the injection is stopped. During the injection, an energetic plasma is formed and is magnetically contained between the mirror regions. Thus, it can be seen that the ion source disclosed herein is useful as a means for initially establishing an energetic plasma in an energetic neutron producing device or a thermonuclear experimental device.

The source is additionally useful in providing ions in a magnetic field for measuring the charge exchange and scattering cross-sections of ions of a particular material. Also, a very important property, the ion diffusion rate, may be determined for any particular type of injected ions. In addition, the ion source of this invention may be used as an initial source of ions for a particle accelerator. The ions, after spiraling a certain distance within a uniform magnetic field, can be fed into the particle accelerator where the ions are given a further acceleration.

Figure 1 illustrates one embodiment in which the principles of this invention may be carried out. In this embodiment, all the components are supported from a combined T-shaped insulating support and vacuum connection 1. Connection 1 may be constructed from Pyrex, for example. Closing one side of the T connector is a support flange 2 and associated equipment attached thereto. Closing a portion of the opposite side of the T connector is a ground flange 3. The bottom of the T connector is affixed to a vacuum line (not shown), and the top is either capped or connected to vacuum.

Attached to the support flange 2 is a hollow, stainless steel, support tube 4 which extends through the T connector 1 and ground flange 3 toward the electrode end of the source assembly. Support tube 4 is formed of an inner and an outer tube supplied with cooling water therebetween. A hollow, stainless steel, source tube 5 is coaxially aligned within support tube 4 and extends through the support flange 2 into the atmosphere. Source tube 5 is provided with means 6 for imparting rotational adjustment to tube 5 with respect to tube 4. Means 6 is affixed to support flange 2 and provides for axial adjustment of tube 5 with respect to tube 4. Attached to the opposite end of source tube 5 is a tantalum, ion source head 7. Appropriate cooling lines 8, 8', and a gas feed tube 9 extend through source tube 5 and head 7. Com-

pression type seals, not shown, are used as vacuum seals around the lines within source tube 5, and an O-ring seal 10 is used between source tube 5 and support tube 4.

A perforated, stainless steel, ground shield 11 is supported from the ground flange 3 and extends perpendicularly in both directions therefrom. Shield 11 has blisters 12 to co-act with drain fins 13 positioned upon support tube 4 and source head 7 for electron "dumping." Also supported from ground flange 3 is a perforated, cylindrical, stainless steel, accelerating electrode support tube 14. Enclosing tube 14 is a glass tube 22. Tube 14 and flange 3 are connected to ground by a member 20 and lead 21.

Positioned within the extremity of source head 7 are appropriate source components. These consist of a generally circular filament 15 backed with a shield 16, a cylindrically apertured defining electrode 17, and an insulated reflector or terminal electrode 18. Gas is fed to the aperture of electrode 17 through gas feed tube 9 from a source of gas, not shown. A radially perforated accelerating electrode 19, supported from the electrode support tube 14, encompasses the terminal electrode 18. The openings in accelerating electrode 19 and in electrode 17 are three radial slits with narrow bridges between them. The three bridges of each electrode are spaced 120° apart, and the slits in electrode 19 are aligned with those in electrode 17. The region between the defining electrode and the terminal electrode forms the arc chamber from which ions are withdrawn by the accelerating potential. As can be more clearly seen from Figure 2, the radial openings in accelerating electrode 19 are slightly off-set with respect to the opening between electrodes 17 and 18 so that a strong electrostatic field is impressed on the arc on one side and a weaker field on the other. This results in bowing of the arc meniscus, as shown. Since ions leave at a right angle to the arc meniscus, they are injected at an angle into a magnetic field H and are caused to spiral by the magnetic field and thus miss the source on the first and subsequent revolutions. The field H is provided by electromagnets, not shown.

Glass tube 22 enclosing the device may be mounted in one end of a neutron producer or a thermonuclear device such as disclosed in the application of Albert Simon, Serial No. 732,770, filed April 28, 1958, or the application of P. R. Bell et al., Serial No. 753,846, filed August 7, 1958, for initially forming an energetic plasma. The ion source may be positioned in the magnetic mirror region in the one end of the device such that ions accelerated from the source are injected at a traverse angle, as discussed above, and spiral within a time rising containing magnetic field between the mirror regions. After the energetic plasma is formed, the ion source is removed and the plasma may then be sustained by means such as set forth in the co-pending application Serial No. 814,939, filed May 21, 1959, of Bell et al.

Glass tube 22 may also be mounted in one end of an evacuated enclosure, not shown, which is provided with a containing magnetic field. The charge exchange cross-section, scattering and ion diffusion properties of the ions injected from the source may then be determined.

Tube 22 may also be mounted in one end of an evacuated enclosure, not shown, which is provided with a uniform magnetic field. A particle accelerator, not shown, may be located at the other end of the enclosure in such a position that ions, injected into the uniform magnetic field from the source, will spiral through the field and enter the particle accelerator where they are further accelerated.

In operation, the device of Figure 1 is connected to 70 vacuum pump through connection 1. The pressure in the device is lowered to a value of about 10^{-5} mm. Hg. The magnetic field H is established at a value depending on the device in which the ion source is used. The field strength may be in the range from 6 to 105 kilogauss. 75

The filament 15 is made of tantalum and is heated by a direct current of 350 amperes by means, not shown. The filament support clamps are of copper and are water cooled with water supplied through tubes 8'. The source head 7 is also water cooled by water supplied through tubes 8.

A potential gradient of about 150 volts is established by a conventional power supply between filament 15 and defining electrode 17. Electrons are drawn from the filament by this potential gradient. Gas, such as hydrogen, deuterium, or a mixture of deuterium and tritium, is admitted to the slot in electrode 17 and is ionized by the electrons drawn from the filament. Primary electrons are reflected back into the arc 23 by reflector 18 since the reflector 18 assumes a negative potential, with respect to the defining electrode 17, and is equal to that of the filament 15. The ion accelerating voltage is applied between the defining electrode 17 and the accelerating electrode 19 so as to draw ions from the arc in a traverse direction as discussed above.

It may be desirable to substitute a small solid arc discharge for the cylindrical arc discharge of Figure 1. Such a solid arc discharge is shown in Figure 3. A solid arc 23' is established between a filament 15' and terminal electrode or reflector 18'. The defining electrode 17' is appropriately apertured for a solid arc, and gas is fed from a line 9' into the aperture in electrode 17'. A cup-shaped accelerating electrode 19' is provided with radial openings that are slightly off-set with respect to the radial openings in reflector electrode 18'. As in Figure 1 discussed above, electrons are drawn from filament 15' by a potential gradient between filament 15' and defining electrode 17'. Gas, such as used in Figure 1, is fed through tube 9' and into the defining aperture of electrode 17', where it is ionized by the electrons to form an arc discharge 23' which refluxes between filament 15' and reflector electrode 18' in a manner similar to that for Figure 1. A potential gradient between electrode 17' and accelerating electrode 19' and the off-set relationship between the radial openings in electrodes 18' and 19', will cause ions to be accelerated through said openings in such a direction that they will spiral into the magnetic field "H" and will not return to strike the source when the source is used in a magnetic mirror device such as discussed above for Figure 1.

The ion source of Figure 1, when operated in a magnetic field of 6000 gauss, produced an arc current of about 0.250 ampere, or a density of about 0.750 ampere/in.² of arc area. On the other hand, the ion source of Figure 3, when operated in a magnetic field of 6000 gauss, produced an arc current of 0.175 ampere, or a density of about 2.0 amperes/in.² of arc area.

Thus, it can be seen that we have provided an ion source which can be used to inject ions into a mirror-type machine at a large angle with respect to the axis of the machine and still prevent the ions from returning and striking the source.

This invention has been described by way of illustration rather than limitation and it should be apparent that the invention is equally applicable in fields other than those described.

What is claimed is:

- An improved ion source comprising a support flange, a ground flange, a T-shaped insulating support and vacuum connection affixed to and disposed between said flanges, a support tube affixed to said support flange and extending through said ground flange in spaced relation thereto, a source tube disposed within and spaced from said support tube, an ion source head affixed to said source tube, means disposed within said source head for initiating a gas-fed refluxing arc discharge therewithin, comprising a heated filament electrode, an electrically floating anode disposed in spaced relation to said filament electrode, an apertured arc defining electrode disposed between said filament electrode and said anode in spaced

relation thereto, means for connecting a potential gradient between said filament electrode and said arc defining electrode, a cup-shaped accelerating electrode disposed around said anode and provided with a plurality of radial openings, means connecting said accelerating electrode to ground, a source of gas, a gas feed tube, means for feeding gas from said source and through said gas feed tube into the aperture of said arc defining electrode, said gas being ionized by electrons drawn from said filament electrode by said potential gradient to thus form a refluxing arc discharge through said arc defining electrode and between said filament electrode and said anode, means for establishing a magnetic field parallel to said discharge, said radial openings in said accelerating electrode being slightly off-set with respect to the spacing between said defining electrode and said anode, whereby ions are accelerated out of said arc discharge by said accelerating electrode and at a traverse angle with respect to the direction of said magnetic field such that said ions will spiral into said field and away from said discharge and will not return to strike said discharge.

2. The ion source set forth in claim 1, wherein said support tube and said source head are enclosed within a cylindrical, grounded, perforated shield member, said shield member being provided with a plurality of blisters, a plurality of drain fins mounted on said support tube and said source head, one each of said fins being disposed in one each of said blisters to thus form a plurality of electron dumps.

3. The ion source set forth in claim 1, wherein the filament electrode is in the shape of a ring, and the arc discharge formed between said filament electrode and said anode through said arc defining electrode is cylindrical.

4. The ion source set forth in claim 1, wherein the filament electrode is a small solid plate, and the arc discharge formed between said filament electrode and said anode through said arc defining electrode is a small solid arc.

5. The ion source set forth in claim 1, including means for cooling said source head, said support tube, and said filament electrode.

6. An improved ion source comprising a source head, means for supporting said head, means disposed within said source head for initiating a gas-fed refluxing arc

discharge therewithin, comprising a heated filament electrode, an electrically floating reflector electrode in axial alignment with said filament electrode, an apertured arc defining electrode disposed between said filament electrode and said reflector electrode in spaced relation thereto, a source of gas, means connected to the aperture within said arc defining electrode for feeding gas thereto from said source, means for connecting a potential gradient between said filament electrode and said arc defining electrode, a cup-shaped accelerating electrode disposed around said anode and provided with a plurality of radial openings, means connected to said accelerating electrode for providing an accelerating potential between said arc defining electrode and said accelerating electrode, said gas within the aperture of said arc defining electrode being ionized by electrons drawn from said filament electrode by said potential gradient to thus form a refluxing arc discharge between said filament electrode and said reflector electrode through said arc defining electrode, means for establishing a magnetic field parallel to the direction of said discharge, said radial openings in said accelerating electrode being slightly off-set with respect to the spacing between said defining electrode and said reflector electrode such that ions are accelerated out of said arc discharge by said accelerating potential and at a traverse angle with respect to the direction of said field, said ions spiraling into said field and away from said discharge so as not to return to strike said discharge.

7. The ion source set forth in claim 6 wherein the filament electrode is in the shape of a ring, and the arc discharge formed between said filament electrode and said reflector electrode through said arc defining electrode is cylindrical.

8. The ion source set forth in claim 6, wherein the filament electrode is a small solid plate, and the arc discharge formed between said filament electrode and said reflector electrode through said arc defining electrode is a small solid arc.
